RAILWAY CAR END BUFFER ARRANGEMENT

Filed Oct. 24, 1947

2 SHEETS—SHEET 2

INVENTOR

Albert G. Dean

ATTORNEY

ATTORNEY

The car body to which the invention is shown applied is generally designated by the numeral 10, its end wall by 11, and its underframe by 12. This car body end is shown equipped with side buffers, generally designated 13, and a central combined buffer 14 and diaphragm face plate 15, both types of buffers being mounted for cushioned inward movement on the underframe, and the combined buffer member and face plate being mounted also for pivotal movement about an axis in substantially the central vertical longitudinal plane of the car body and also for limited cushioned lateral and/or vertical movements, as will be made clear by the detailed description later on. Both the side buffers 13 and the central buffer 14 are mounted on the underframe 12 through longitudinally spaced aligned guiding and supporting means cooperating with stems extending inwardly from the respective buffers. Springs are also associated with each of the stems to normally hold them in an outward position.

According to the invention, the stems, the outer guiding and supporting means and the springs are designed so they may be assembled as separate subassemblies, and these subassemblies are so related to the associated parts of the end underframe that they may be assembled by endwise movement with the underframe and removably secured thereto by a simple securing operation.

Referring first to the mounting of the side buffers 13, it will be seen that the end sill 16 of the underframe is provided with an opening therethrough adapted to receive the buffer stem 17 secured at its outer end to the buffer member or head 18, the inner end of the stem being guided and supported by an outwardly opening pocket 19 integral with the underframe 12 and extending inwardly of the end sill. The outer end of the stem is supported and guided by a collar 20 on a bracket 21 which is removably bolted by bolts 22 to the outer face of the end sill 16.

Inwardly of the end sill the stem is provided with an enlarged abutment 23 receiving the thrust, through a spring-centering collar 24, of the outer end of a spring, such as the coil spring 25, encircling the stem. The abutment 23 may be a two-part clamp interlocked with a groove in the stem by the clamping bolts 23'.

The inner end of the stem is supported and guided by a floating follower 26 against which the inner end of the spring 25 is adapted to bear. The inner end of the stem, which projects, in the arrangement shown in Figure 2, some distance beyond the pocket 19, is preferably threaded, and a nut 27 is screwed thereon and suitably locked in place. This nut forms an enlargement at the inner end of the stem which is adapted to engage the floating follower 26 on its inner side to hold the parts of the subassembly together when it is withdrawn from the underframe. A rubber cushion 27' is preferably provided at the inner end of the follower.

The inner end 28 of the pocket 17 is formed with a central opening 29 to permit passage of the nut and the portion of the follower 26 projecting therethrough, and the end wall of the pocket surrounding this opening provides an inner abutment through which the thrust of the spring 22 is transmitted by way of the follower 26 to the underframe 12.

The distance between the abutment 23 on the stem 16 and the abutment 28 on the underframe is less than the uncompressed length of the spring, and the mounting bolts 22 are of a greater

length than is necessary to bolt the bracket 19 to the end sill. This greater length makes it possible to start the nuts of the bolts with the spring under no, or substantially no, compression, but by the time the nuts are fully screwed home, the spring is placed under a predetermined precompression in the assembly of the buffer subassembly with the underframe. The nuts 22 may then be locked by suitable means, such as locking nuts.

It will be noted that the buffer stem is comprised of two telescoping parts, the stem proper 17 and a sleeve 30 which surrounds the stem proper 17. The outer end of this sleeve 30 abuts the buffer head 18 and the inner end of the sleeve has clamped to it the abutment 23. In the arrangement shown in Figure 2 this sleeve acts as if it were an integral part of the stem in the operation of the buffer on the inward buffering movement thereof, but the buffer stem proper 17 and the attached buffer head 18 are free to move outwardly in the sleeve to the extent permitted by the nut 27.

This is the arrangement, when the adjacent cars are coupled together by the usual coupler heads 29, in which the side buffers of the coupled cars are slightly spaced apart, as shown in Figure 2, and the buffers come into play only upon the approach movement of the cars in buff or in rounding curved track.

When the cars are coupled together by a different coupling, as represented by the hooks 30 suitably connected as by a flexible chain or cable (not shown), it is desirable that the side buffers are in strong buffering engagement at all times while the cars are coupled, and it is therefore desirable that the buffers come to rest in their outermost position a substantial distance beyond the position shown in Figure 2. This can be achieved, as shown in Figure 3, by first manually pulling out the buffer head 18 and stem proper 17, which can be done without spring opposition, and an adapter 31 is then dropped on the stem proper 17 between the buffer head and the sleeve 31. This adapter has a slot which fits the rectangular shape of the stem and may be carried, at times when it is not in use, on the car end, where it is in place for use when required.

In Figure 3 the buffers of two coupled cars are shown in the partially compressed condition which they assume under this modified coupling condition. The side buffers are provided with relatively heavy springs to take heavy buffering forces. The central buffer 14, forming part of the face plate 15, is mounted generally similarly to the side buffers except as modified to permit the lateral and vertical cushioned movement thereof. The upper part of the face plate is urged outwardly by a spring, as 32 (Figure 1), and the sides and top of the face plate are connected to the car body by the usual enclosing diaphragm 33.

With this arrangement, the combined buffer 14 and face plate 15 are carried by the side stems 34 hinged to the buffer by the vertical hinge pins 35 and extending inwardly through openings in the end sill, and supported and guided by an outer supporting and guiding means 36 and an inner supporting and guiding means 37. The outer supporting and guiding means comprises a bracket 38 loosely receiving the rectangular outer end portion of an associated stem. Inwardly of the end sill the stem is of circular form and provided with an abutment 39 bearing against a shoulder on the stem for the outer end of a coil spring 40 surrounding the stem. The inner end of the stem is guided and supported through a

floating follower 41 engaged by the inner end of the spring 40 and carried by an outwardly opening fixed pocket 42 rigidly mounted on the underframe 12. The inner end of the stem is screw-threaded, and a nut 43, threaded thereon and suitably locked, provides an enlargement for engagement with the inner end of the follower 41 to hold the parts assembled when the buffer sub-assembly is outwardly withdrawn from the underframe.

The subassembly, including as main elements the bracket 38, stem 34, spring 40 and follower 41, may be subassembled as a unit and inserted longitudinally in assembled relation with the underframe where it is removably secured by bolting the bracket 38 to the outside face of the end sill of the underframe (see Figures 2 and 5). It will be seen then that by unbolting the outer mounting brackets of the side stems, the side stem subassemblies, together with the buffer and face plate, may be removed as a unit from the car end underframe.

The side stems are preferably cushioned by a spring in their outer mountings 36, and to this end a rubber cushion 44 of generally laterally presenting U-shape (Figure 5) is inserted between the rectangular-shaped guide of bracket 38 and a U-shaped metal plate 45 which bears against the rectangular portion of the stem 34. This rubber cushion is designed to fit between the top, bottom and one side, as shown the laterally outer side, of each stem and the guide opening in the supporting bracket 38. The stem in the region where it slides in and out through this cushion is preferably furnished with wear plates 46 on the sides facing the cushion.

This cushioned mounting of the side stems of the combined buffer 14 and face plate 15 permits the limited lateral and/or vertical movement of the associated face plate to prevent sliding of one face plate on the associated face plate of an associated coupled car during the normal relatively straight-track operation of the cars. It greatly reduces the wear and noise generally caused by the relative movements of the two opposed face plates of coupled cars.

The operation of the device is believed clear from the foregoing detailed description, and further description of the operation is therefore omitted.

While a specific embodiment of the invention has been herein described in detail, it will be understood that changes and modifications may be made by those skilled in the art without departing from the main features of the invention, and such changes and modifications are intended to be covered by the appended claims.

What is claimed is:

1. A railway car end buffer arrangement comprising, in combination, a car end underframe, a buffer member disposed longitudinally of the car outside said end underframe and supported therefrom for in-and-out movement by at least one stem extending inwardly therefrom and supported and guided by longitudinally spaced outer and inner supporting and guiding means carried by said underframe, and spring means for urging said buffer member and said stem outwardly, said buffer member, said stem, said spring means and said outer supporting and guiding means being removably assemblable as a unit with the car end underframe.

2. A railway car end buffer arrangement comprising, in combination, a car end underframe having an end sill and an outwardly open pocket

disposed inwardly of said sill and having a restricted opening at its inner end forming an abutment, and a buffer subassembly adapted to be assembled with, or disassembled from, the end underframe by endwise movement, said subassembly comprising at least one buffer stem, a guide for said stem adapted to be removably secured to said end sill, the stem extending inwardly through said pocket and having an enlargement at its inner end of less diameter than the diameter of the opening at the inner end of said pocket, a follower movably mounted on the inner end of said stem and guiding the latter in said pocket, a spring surrounding said stem and extending between an abutment on the stem and said follower, the inner end of said follower being adapted to engage the abutment at the inner end of said pocket to compress the spring when the buffer stem is moved inwardly and the enlargement at the inner end of said stem being adapted to engage the follower to hold the parts assembled when the buffer subassembly is withdrawn from the underframe.

3. A railway car end buffer arrangement comprising, in combination, a car end underframe, a buffer member disposed longitudinally of the car outside the car end underframe and supported therefrom for in-and-out movement by at least one stem extending inwardly from and operatively connected with said buffer member and supported and guided by longitudinally spaced outer and inner supporting and guiding means carried by said underframe, and spring means for urging said stem outwardly, means for removably mounting said buffer, said stem, said spring means and said outer mounting means as a unit on said underframe, said removable mounting means being adapted to precompress said spring while mounting said unit in place.

4. A railway car end buffer arrangement comprising, in combination, a car end underframe, a buffer comprising at least one inwardly extending stem supported and guided on the underframe by an outer guiding and supporting means removably secured to the underframe and an inner guiding and supporting means rigidly secured to the underframe, a spring for urging said stem outwardly reacting against the stem and the car underframe, said stem, its outer guiding and supporting means and said spring being removably assemblable as a unit with the car end underframe.
